UNITED STATES PATENT OFFICE.

OCTAIVE S. PAYZANT, OF NEW YORK, N. Y.

REVOLVING DUPLEX TICKET CABINET.

Application filed April 6, 1923. Serial No. 630,324.

To all whom it may concern:

Be it known that I, OCTAIVE S. PAYZANT, a citizen of the United States, and a resident of the city of New York, borough of Manhattan, in the county and State of New York, have invented a new and Improved Revolving Duplex Ticket Cabinet, of which the following is a full, clear, and exact description.

10 This invention relates to a system of ticket dispensing devices and particularly to an improved arrangement of revolving ticket cabinets and their association together and with windows whereby a maximum number 15 of cabinets may be associated with each window.

Another object of the invention is to provide an arrangement of ticket cabinets whereby four independent sets of tickets are 20 conveniently positioned in respect to each window through which the tickets are dispensed.

A still further object, more specifically, is to provide an arrangement of cabinets in 25 connection with dispensing windows for railroad stations whereby the various cabinets may be rotated and either face presented to the ticket agent.

In the accompanying drawings—

30 Figure 1 is a horizontal sectional view through part of a set of ticket windows and associated devices including rotatable cabinets co-acting with the windows, said arrangement embodying certain features of 35 the invention.

Figure 2 is a sectional view through Figure 1 approximately on line 2—2.

In railroad stations and elsewhere is found certain space allotted for the selling or 40 dispensing of tickets and this space is usually enclosed by a wall having a large number of windows through which the tickets are dispensed. Back of the windows are arranged cabinets or holders of some kind for 45 retaining the tickets before they are dispensed. In order to serve a large territory these cabinets heretofore have been very large and more or less cumbersome so that usually only one cabinet or holding device 50 was possible for each window and when a particular ticket seller left his window, it would be closed. It is the practice in rail-

road and other ticket selling booths to charge the tickets in a given cabinet to a particular seller who is responsible for all 55 the tickets and, consequently, when that seller leaves the window he locks up his cabinet or booth and closes his window so that no one can molest his tickets.

If a ticket seller works 8 hours each day, 60 there will be 16 hours when his window will be closed. In order to serve the public a large number of windows have heretofore been provided so that when one ticket seller leaves after having completed his day's work, another ticket seller will report for duty and will open another window and sell from another cabinet. In large cities, the demand for tickets is so large that an extremely 65 large place is required for each railroad to 70 properly serve the public in dispensing tickets. In order to reduce this space and yet provide ample service for the public, the present invention contemplates the use of specially constructed cabinets whereby four 75 sets of tickets may be dispensed from the same window and each set will be arranged so as to be independent of the other set and capable of being sealed against use by anyone but the proper ticket seller. 80

As shown in Figure 1, the various windows 1 are of the usual size and provided with wall structures 2 arranged therebetween, a central point of the various wall structures 2 usually being approximately 85 five feet apart and the window usually being approximately three feet wide though these particular measurements are not arbitrary. Arranged adjacent the respective windows 1 is an inner counter 3 and an outer counter 90 4 which may be on different levels as indicated in Figure 2. Arranged a suitable distance back of the counter 3 are wall sections 5 which may be open mesh work if desired and also connected together by suitable bracing bars if preferred. From the center of each of the wall sections 5 is arranged a horizontal bar 5' as shown in Figure 2 which extends to the front wall 2 whereby there are provided spaced supports for the track 6, which track extends the full length of the series of windows 1 and receives the various carriages 7 connected with the various cabinets 8. Each of 95 100

the cabinets 8 is provided with any desired number of caster wheels 9 whereby the cabinets may be moved longitudinally of the track 6 and by reason of the use of the casters 9 and the pivotal supporting bar 10 which connects the respective cabinets with their carriages, a swinging or rotary movement may be given to each cabinet as indicated in dotted lines in Figure 1. These cabinets are of special construction and are made comparatively thin, usually approximately twelve to fourteen inches thick. Each cabinet 8 is divided into two independent sections by the division walls 11 and 12 and a connecting transverse wall 13. The wall 13 with the division wall 11 divides part of the cabinet so as to present a space 14 for inter-line tickets and a space 15 for local tickets. The wall 13 and wall 12 divides the other part of the cabinet so as to present an inter-line ticket space 14' and a local ticket space 15', said spaces being of the same shape and size as the spaces 14 and 15 and provided with the same ticket receiving pigeon holes, compartments and the like. Preferably a door or several doors are provided for closing the respective spaces 14, 14', 15 and 15'. It will be observed that the space 15' and space 14 act together as indicated particularly in Figure 2. When the doors 16 and 17 are open the ticket seller may sell any ticket desired.

It will be understood that the compartments or sections 14 and 15' contain tickets for the entire railroad system. The opposite half of the section is likewise provided with tickets for the entire railroad system so that the two cabinets for each of the windows 1 contain four sets of independent tickets, each set being the private supply of an independent ticket seller and may be readily sealed against molestation by locking the doors 16 and 17 and any other closures which may be provided, as for instance, the lower doors of the cabinet. When a given ticket seller is selling from a given window, he uses his supply of tickets and when his day's work is done he closes and locks his side of the cabinet. The new ticket seller who takes his place will pull out the cabinet and rotate the same as shown in dotted lines in Figure 1 and then push the cabinet back to its original position. This will allow the second ticket seller to sell from the sections 14' and 15. When the second ticket seller has finished his work and a third seller appears, the second ticket seller closes and locks his cabinet and the third ticket seller unlocks one face of the opposite cabinet. Ordinarily, three ticket sellers to a window is sufficient as each seller works for eight hours. However, if the third or any of the ticket sellers should become sick or should be absent for a day or more, the second cabinet to the window may

be reversed and the fourth supply of tickets for that window may be used by a supply agent or extra ticket seller.

By this method of having reversing cabinets and having each half of the cabinet containing a complete line of tickets, four ticket sellers may use one window so that the window will be in constant use instead of closed as is now the common practice. This arrangement also permits each ticket seller to lock his section of the cabinet and thereby prevent an unauthorized person from molesting his tickets for which he is responsible. This arrangement also will permit two ticket sellers to operate at the same window at the same time and sell tickets from independent cabinets.

What I claim is:—

1. A system of ticket selling booths, comprising a wall provided with a plurality of windows, a pair of ticket carrying cabinets arranged between each pair of windows, each of said cabinets being rotatable and provided with ticket supporting structures on each face. 90

2. A ticket selling or booth system for railroads and the like, comprising a front wall having a plurality of windows and a pair of rotatable ticket carrying cabinets arranged between each window on one face of said wall whereby tickets from opposite sides of each two cabinets may be dispensed through the same window. 95

3. A series of ticket booths, comprising a plurality of windows and a pair of cabinets arranged between each of said windows, each of said cabinets having a set of tickets arranged on each face, and means for rotatably supporting the cabinets in place. 100

4. The combination with a series of windows, of a cabinet arranged between each two windows, each of said cabinets having ticket receiving members on each face whereby either face of the cabinet may be used when dispensing tickets through said windows, supporting means for each of said cabinets, said supporting means permitting a manual rotation of any cabinet and the movement of any cabinet substantially parallel with the windows, and a track associated with said cabinets for guiding the cabinets as they are moved substantially parallel with said windows. 110

5. The combination with a series of windows, of a pair of cabinets arranged in each window, each of said cabinets having ticket receiving members on each face whereby either face of the cabinet may be used when dispensing tickets through said windows, supporting means for each of said cabinets, said supporting means permitting a manual rotation of any cabinet and the movement of any cabinet substantially parallel with said windows, and a track associated with said cabinets for guiding the cabinets as they 120

125

130

are moved substantially parallel with said windows.

6. The combination with a series of windows having a wall space between the respective windows, of a pair of cabinets arranged opposite each of the wall spaces, each pair of said cabinets being approximately

equal in thickness to the wall space whereby substantially the entire window space is left for the ticket seller when dispensing from the cabinets, each of said cabinets being rotatable and formed with identical ticket receiving members on each face. ¹⁰
